INVENTOR.

UNITED STATES PATENT OFFICE.

JOHN GAEL BROWN, OF EVANSTON, ILLINOIS.

DESIGN FOR A MAGIC-LANTERN ATTACHMENT.

SPECIFICATION forming part of Design No. 32,089, dated January 9, 1900.

Application filed August 12, 1899. Serial No. 727,077. Term of patent 3½ years.

To all whom it may concern:

Be it known that I, JOHN GAEL BROWN, a citizen of the United States, residing at Evanston, in the county of Cook and State of Illinois, have invented and produced a new and original Design for a Magic-Lantern Attachment, of which the following is a specification, reference being had to the accompanying drawing, forming part thereof.

10 A represents a square plate supporting a square projection B, open at opposite ends and closed at top and bottom to admit magic-lantern views.

15 C is a raised projection cylindrical in shape and projecting from B.

D D D D are wire loops, the ends of which are beaded into the perpendicular sides of the plate A.

Having described my invention, what I claim as new, and desire to secure by Letters 20 Patent, is—

The design for a magic-lantern attachment, as herein shown and described.

JOHN GAEL BROWN.
